UNITED STATES PATENT OFFICE.

HARRY LANDSIEDEL, OF CINCINNATI, OHIO, ASSIGNOR TO DALTON ADDING MACHINE COMPANY, OF CINCINNATI, OHIO, A CORPORATION OF OHIO.

KEY-CONTROL MECHANISM FOR ADDING MACHINES.

Application filed September 7, 1922. Serial No. 586,611.

To all whom it may concern:

Be it known that I, HARRY LANDSIEDEL, a citizen of the United States, residing at Cincinnati, in the county of Hamilton and State of Ohio, have invented certain new and useful Improvements in Key-Control Mechanism for Adding Machines, of which the following is a specification.

The object of this invention is to provide means to insure the proper functioning of all the various keys such as the numeral keys, total key, subtraction key, nonadd key, back space key, correction key or other special keys which may be used in conjunction with the regular numeral keys. It is the custom in adding machine construction to provide locks to control the various keys against depression when the operating lever is in a forward position, and the ordinary method is to furnish an individual lock for each key. In the present invention, all of the keys, including the numeral keys, are controlled by one locking member, thereby eliminating numerous parts and complications.

Another object of the invention is to provide means for latching down the feature keys, such as the total, sub-total, subtraction, and non-add keys, so that it is unnecessary to hold the selected key down while operating the lever.

Another feature of the present invention pertains to the provision of a key known as a release key which may be employed to restore any key that was accidentally or inadvertently depressed, and a further object is to prevent the machine from being operated if any key is partially or incorrectly depressed.

A still further object is to prevent an operator from restoring the keys that have been depressed to their normal position after the operating lever is started forward, and also to prevent the depression of the various keys after the operating lever has been partially pulled forward. These and other improvements are made possible by this device which will be called hereinafter the universal key control mechanism.

The accompanying drawings illustrate the device as applied to a Dalton adding machine, although it is, of course, obvious

that its use is not restricted to this particular make of machine.

In the drawings, only so much of a complete adding machine is illustrated as is deemed necessary to disclose the construction and arrangement of the key control mechanism and associated parts in its operative relation to the various keys employed, and it will be understood from the present description that the special keys to be hereinafter referred to are described by way of illustration of the capacities of the control mechanism and that it is not the intention to limit the invention to the use of the particular special keys indicated, since it is evident that additional special keys of like or similar character might be used or that the particular keys hereinafter to be described might, by the provision of suitable connections, be invested with capacities other than those specifically mentioned without change in the form and construction of the key itself or its mode of co-operation with the control mechanism. From the above it will be evident that the name hereinafter given to any particular key is to be merely employed for purposes of convenient description and that the same or other like key might be employed to control other portions of the mechanism without substantial change or modification.

In the drawings:

Fig. 1 is a side elevation of a Dalton adding machine showing only so much of the interior mechanism as is needful for a correct understanding of the present invention;

Fig. 2 is a front elevation of the machine, partially broken away to better illustrate the key control mechanism and associated parts;

Fig. 3 is a side elevation of the key control mechanism with the back space key and subtraction key at the extreme right of the machine removed to better illustrate the remaining mechanisms;

Fig. 4 is a similar view showing the relation of the parts with one of the numeral keys depressed;

Fig. 5 is a similar view showing the total keys depressed;

Fig. 6 is a view showing in normal posi-

tion the mechanism for latching down the feature keys that are to remain depressed during the operation of the machine;

Fig. 7 is a similar view showing the same mechanism in the position it assumes when the total key or any feature key is depressed;

Fig. 8 is a view similar to Fig. 7 except that the mechanisms are illustrated in the position assumed when the operating handle is moved to its extreme forward position which releases the latch and thereafter permits all parts to be restored to normal position.

Fig. 9 is a front view of the key bank and associated parts; and

Fig. 10 is a detail of the subtraction key and associated parts.

The features of the invention, as shown, are embodied in an adding machine of the Dalton type which is provided near its upper rear portion with a transversely extending rock shaft 1 which supports a series of type carriers 2 of arcuate formation together with adding racks 3, which carriers and racks are oscillated to varying positions in a manner well understood in the present art. The type carriers co-act with a platen 4 which carries the paper to receive impressions from the types which are driven to print by the usual hammers 5. The ink ribbon mechanism and the accumulating mechanism are not illustrated, since they have no direct bearing on the present invention.

Numeral keys 6, arranged in two banks, occupy the usual position at the front of the machine and range from zero to nine inclusive. The numeral keys are mounted upon the upturned forwards ends of key levers 7 which are fulcrumed in the usual manner at the point 7^a (see Fig. 1), and each of the key levers, operates against the tension of a spring 10^a and at its rear end is provided with an upturned tappet 8 for the purpose of positioning the various stops 9 in the transversely movable carriage 10. The usual main operating shaft 11, which carries the handle, is provided with a full stroke sector 12 which co-acts with a full stroke pawl 13, so that a partial forward movement of the handle and shaft will be prevented. All of the above mechanisms are well understood in the art and need not be referred to in more complete detail.

The parts now to be described pertain more directly to the key control mechanism of the present invention. At a point slightly in advance of the main operating shaft, is located a transversely extending rock shaft 14 which is journaled at its left end in the side frame 15 of the casing and is journaled at its right end in an upstanding bracket 16 secured to the base of the frame as best shown in Fig. 2. Rigidly pinned to the rock shaft 14 are a pair of L-shaped arms 17 and

18 near the left and right ends respectively of the shaft, and the forward extensions of these arms serve to carry and support a cross bar 18^a which, with its supports, constitutes a swinging bail which will be raised and lowered by a rocking movement of the shaft 14.

Rigidly secured to the left end of the shaft 14, and movable therewith, is an arm 19 which carries at its upper end a roller 20 which works in a cam slot 21 in the forward end of a universal pawl lever 22 fulcrumed upon a stud 23 which extends inwardly from the side frame 15 of the machine. The rear end of the pawl 22 is provided with a roller 24 co-operating with a segment 25 mounted upon the main operating shaft 11 and rocking therewith.

Riveted to the forward upper corner of the segment 25 is a stop block 26 which, as shown in Fig. 3, normally lies below the roller 24 and in position to sweep under said roller with the parts in the position indicated. When, however, the roller 24 is depressed as indicated in Fig. 4, the stop block 26 will abut directly against the rear end of the control pawl lever 22 and prevent any rocking movement of the segment 25, and thereby prevent movement of the operating handle.

The control mechanism, when actuated by the numeral keys, is designed to throw the control pawl lever 22 into the stopping position indicated in Fig. 4, and the functioning of the numeral keys in this connection will now be described. In Fig. 3 it will be observed that each of the numeral key levers rest directly upon the control bar or bail 18^a when in elevated position. When any numeral key lever is depressed as indicated in Fig. 4, the bail will be carried down and the shaft 14 rocked accordingly which oscillates the arm 19 and carries the roller 20 within the cam slot 21 into the intermediate position indicated in Fig. 4. A movement of this extent results in a swinging down of the control pawl 22 into the stopping position indicated from which it is evident that when a numeral key lever is depressed, the handle cannot be operated until the key lever is again released and the parts restored to normal position.

The machine is provided with the usual correction key to enable the movable stop carriage to be restored to its normal position in case an error is made when depressing any one of the numeral keys. As shown in Fig. 4, the correction key lever 27, of arcuate form, is pivoted upon the rod or shaft 28 and terminates in a convenient position to be operated from the front of the machine. The lower portion of the lever 27 is provided with a cam face 29 which is adapted to contact a roller 30 which is mounted upon the side of a stub key 59 fixed to shaft 14

which acts as a part of the bail mechanism, so that when the correction key is depressed, the cam face 29 will move the bail down and the universal pawl 22 will take the position indicated in Fig. 4, locking the main shaft and operating handle against movement until the correction key is restored to its normal position by the action of a spring 28^a (see Fig. 4), which connects the correction lever 27 with any suitable fixed portion of the structure.

A back space key lever 31 is pivoted on a stud 32 inwardly extending from the right side frame of the structure as indicated in Fig. 1, and this lever, like the inwardly extending key levers, lies directly over the universal bail bar 18^a, so that when the back space key is depressed it will move the universal key control bail down, and the pawl 22 will take the position indicated in Fig. 4.

It is obvious from the above description that the numeral keys, the back space key, and the correction key, must be restored to their normal positions after being depressed and thereby complete their respective functions and that the machine cannot be otherwise operated.

Attention is now directed to those keys which are designed to remain depressed during the operation of the machine. A total shaft 33 is journaled at its ends by the two main side frames. Rigidly mounted on the right hand of said shaft is a total key lever 34 operating against the tension of a spring 34^b and to the left of the total key lever, and likewise rigidly pinned to the total shaft 33 is a depending arm 35 provided at its lower end with an inturned ear 36 which normally occupies a position, as shown in Fig. 3, closely adjacent to a slot 37 formed in the rear upper portion of the L-shaped arm 18, so that when the total key is depressed, it will directly engage with the slotted portion of the arm 18 and thereafter swing the arm forwardly depressing the bail to the extreme position indicated in Fig. 5. In this case, however, the bail bar is given a greater movement than when operated by the keys which must be restored to their normal position before the machine is operated. This additional movement causes the roller 20 to move to the extreme lower end of the cam slot 21 and the lower half of this movement, reverses the effect of the initial movement on the control pawl 22, that is to say, the rear upper end of the control pawl after being initially depressed is afterwards lifted into the position indicated in Fig. 5, so that the segment 25 on the handle operated shaft 11 will be free to advance to the position indicated in dotted lines. During this movement, however, the bail and associated parts will be maintained in the depressed position indicated, and this will serve to hold the total key lever in its re-

tracted position until the handle stroke has been completed.

The subtotal key lever 34^a is freely mounted upon the shaft 33 and is intended when operated to act against the total key lever 70 and carry the same back with it, so that the subtotal key lever merely functions through the total key lever in so far as the operation of the universal control bail is concerned.

Pivoted on the shaft 33 is the subtraction key 38 (see Fig. 9) which is of generally U-shape and is provided on its under edge with a cam face 39 in proximate relation to the universal bail bar 18^a, so that when the subtraction key is depressed, the cam face will move the bail bar 18^a down in the same manner and to the same extent as during the operation of the total key which will result in the maintenance of the subtraction key in its depressed position during the operation of the handle.

The most satisfactory way of controlling the feature keys that are to remain depressed during the operation of the machine is to have them latch down when depressed by the operator. To accomplish this a latching device is provided to latch the universal bail down when any such key is depressed. This relieves the operator from the necessity of holding down the key after depression and until the handle is initially pulled. The latching device 40 is particularly illustrated in Figs. 6, 7 and 8. The latch is in the form of a depending doubly curved bar which is pivoted to the shaft 33 and normally occupies the position indicated in Fig. 6 in which its acting lower end lies in front of and above the plane of the bail bar 18^a. A retaining latch 40^a has a finger 40^b which normally engages the latch 40 and holds the same in the position shown in Fig. 6 until depressed by the lowering of the bail 18^a which carries down the retaining latch into the position shown in Fig. 7. Integral with the latch 40 is an upper extension member 41 which is acted upon by a spring 42 secured to some convenient portion of the structure, which spring will cause the lower or acting end of the latch to move rearwardly when released to occupy a position immediately above the bail bar, as shown in Fig. 7.

Mounted on the front panel 42^a is a release key 43 riveted into a flexible spring arm 44 secured at its lower end at the point 45, so that when the key 43 is depressed, its inner end will bear against the forward end of the extension 41 and carry the same back to move the latch 40 from its stopping position indicated in Fig. 7 to the normal position indicated in Fig. 6. This enables a restoration of any feature key that was depressed through inadvertence or mistake.

Pivoted on the bracket 16 is a retaining pawl 46 actuated by a spring 47. This pawl co-acts with a square stub 48 laterally ex-

tending from the latch 40 near the acting end thereof. When any key is depressed that is intended to remain down during the operation of the machine, the universal bail 5 receives the full movement and the lower portion of the latch 40 will be released by the finger 40^b and swung rearwardly by the action of the spring 42 until it swings over and engages with a stud 49 carried by the bail arm 18, and the latch will then hold the bail down and the bail will hold the depressed key down until the main operating shaft 11 reaches the end of its forward movement at which time a swinging cross bar 50 carried by the shaft 11 will contact a rearwardly extending heel 51 rigid with the latch and force the latch forward into the releasing position indicated in Fig. 8, in which position the latch will be held by the action of the pawl 46 which will engage with the square stud 48 on the latch and prevent a return movement thereof.

The universal control bail has been described as having a full movement in connection with the keys that remain down during the operation of the machine and a partial movement with the balance of the keys. This latter movement is resisted by the action of an arm 52 which is pivoted at the point 53 in a slot in the base plate and guided by a slot in the cross plate 55. The arm 52 has secured to its rear end a spring 56 for holding it in raised or normal position, permitting sufficient clearance between the yielding arm and the bail bar for the latter to move when the numeral keys are operated without moving the yielding arm 52, but when any key is depressed that is to remain down during the operation of the machine, the increased depression of the bail will engage the arm 52 and cause it to be depressed against spring tension. The usual key locks 58 are pivoted on the plate 55 intermediate the key levers to prevent two numeral keys from being depressed at one time and in addition to this the stub key 59 is pivoted on the shaft 14 and is guided in one of the slots in the plate 55 and co-acts with the key locks in the usual manner.

When the total, sub-total or back space key is depressed, the forward end of the stub key 59 moves down and spreads the locks 58 thereby preventing any other key from being depressed. Since the stub key moves only in conformity with the movements of the total or sub-total key, it is impossible for the stub key to pass down into its slot when any of the keys on the key-board are depressed in position to spread the key locks, and this arrangement prevents the total or sub-total key from being depressed when a digit or other key on the key-board is down.

The shaft 60 (Fig. 1) supports the electric motor operating lever 61 and also has

rigidly secured thereto a detent 62 which operates an arm 63 on a control shaft 64, which through suitable connections controls the operation of the motor drive clutch mechanism.

From the above description, it will be seen that the universal bail bar and associated parts afford means for controlling and harmonizing the actions of the keys with respect to the various mechanisms with which the keys are individually associated and thereby prevent any maladjustment of the operating mechanisms by reason of an erroneous manipulation of the keys. Since the mechanisms described are wholly independent of the particular formation or arrangement of the setting up mechanism, the printing mechanism, the accumulation mechanisms, and other features usually incorporated in an adding machine, it is obvious that the control mechanisms herein described may be readily associated with various types of adding and calculating machines which utilize all or a part of the various general and special keys hereinbefore described. It is also evident that the mechanism is one which readily lends itself to use with special keys additionally to or other than those particularly described, so that in claiming the invention, it is not the intention to limit the claims with reference to the special work performed by each within the body of the machine, since keys, similarly mounted, might be utilized for functions other than those particularly enumerated.

I claim:

1. In an adding machine in combination with a main operating shaft and stop devices for restricting the movement thereof, a series of numeral keys, a universal control device adapted to be moved by the depression of any one of the numeral keys, means actuated thereby for adjusting the stop mechanism to stopping position, and a special key adapted when depressed to impart an excess movement to the universal control mechanism and thereby move the stop mechanism to a non-stopping position, substantially as described.

2. In an adding machine in combination with a main operating shaft and stop devices for restricting the movement thereof, a series of numeral keys, a universal bail adapted to be depressed by the depression of any one of the keys, means actuated thereby for adjusting the stop mechanism to stopping position, and a special key adapted when depressed to impart an excess movement to the universal bail mechanism and thereby move the stop mechanism to a non-stopping position, substantially as described.

3. In an adding machine the combination of a main operating shaft, a stop mechanism associated therewith, a universal bail underlying all of the numeral keys and adapted

to be depressed by the depression of any one of the keys, a rock shaft to which the universal bail is rigidly secured, and a stop actuating member carried by the rock shaft and adapted when the bail is depressed to adjust the stop mechanism for preventing movement of the operating shaft, substantially as described.

4. In an adding machine the combination of a main operating shaft, a stop mechanism associated therewith, a universal bail underlying all of the numeral keys and adapted to be depressed by the depression of any one of the keys, a rock shaft to which the universal bail is rigidly secured, a stop actuating member carried by the rock shaft and adapted when the bail is depressed to engage the stop mechanism for preventing movement of the operating shaft, and a special key adapted to impart an excess of movement to the bail, said excess movement serving to move the stop actuating member to non-stopping position and to hold the stop key depressed during the oscillation of the main operating shaft, substantially as described.

5. In an adding machine the combination of a main operating shaft, a stop segment carried thereby, a stop engaging arm adapted when in lowered position to engage the forward end of the stop segment and prevent rotation thereof and adapted when raised to ride freely upon the edge of the stop segment, a plurality of numeral key levers, and control means actuated by the movement of any key lever for moving the lowered or stop engaging member to stopping position, substantially as described.

6. In an adding machine the combination of a main operating shaft, a stop segment carried thereby, a stop engaging arm adapted when in stopping position to engage the stop segment and prevent rotation thereof and adapted when in non-stopping position to ride freely upon the stop segment, a plurality of numeral key levers, control means actuated by the movement of any key lever for moving the stop engaging member to stopping position, and a special key lever adapted to impart an increased movement to the stop control means for moving the stop engaging member to non-stopping position, substantially as described.

7. In an adding machine the combination of a main operating shaft, a stop segment carried thereby, a stop engaging arm adapted when in stopping position to engage the stop segment and prevent rotation thereof and adapted when in non-stopping position to ride freely upon the stop segment, a plurality of numeral key levers, control means actuated by the movement of a key lever for moving the stop engaging member to stopping position, and a special key lever adapted to impart an increased movement

to the stop control means for moving the stop engaging member to non-stopping position, and for holding the special key depressed during the oscillation of the operating shaft, substantially as described.

8. In an adding machine the combination of a series of depressible numeral key levers, a swinging bail adapted to be engaged by any one of said levers, a main operating shaft, a segment carried thereby, a pivotally mounted stop arm having its inner end in position, when lowered to engage and stop said segment, and when in raised or normal position to ride freely upon said segment, and a member movable with the bail and engaging said pivoted stop arm for lowering the latter to stopping position when the bail is depressed by one of the numeral key levers, substantially as described.

9. In an adding machine the combination of a series of depressible numeral key levers, a swinging bail adapted to be engaged by any one of said levers, a main operating shaft, a segment carried thereby, a pivotally mounted stop arm having its inner end in position, when actuated, to engage and stop said segment, and when in normal position to ride freely upon said segment, and a member movable with the bail and engaging said pivoted stop arm for moving the latter to stopping position when the bail is depressed by one of the numeral key levers, a special key, connections between the special key and the bail for imparting an excess of movement to the latter when the special key is depressed, the excess of movement serving to return the stop engaging arm to non-stopping position, substantially as described.

10. In an adding machine the combination of a main operating lever, stop mechanisms associated therewith, numeral key levers, a universal control member adapted to be engaged by each of the numeral key levers and moved to control the stop mechanisms, a special key lever adapted to remain depressed during the movements of the operating shaft, said key lever adapted to impart an excess of movement to the universal control member and a latch mechanism adapted to engage the universal control member when moved to its extreme position, to prevent a premature return of the special key lever, substantially as described.

11. In an adding machine the combination of a main operating lever, stop mechanism associated therewith, numeral key levers, a universal control member adapted to be engaged by each of the numeral key levers and moved to control the stop mechanisms, a special key lever, adapted to remain depressed during the movements of the operating shaft, said key lever adapted to impart an excess of movement to the universal control member and a latch mecha-

nism adapted to engage the universal control member when moved to its extreme position, to prevent a premature return of the special key lever, and means associated with the operating shaft for releasing the latch at a predetermined point in the movement of the operating shaft, substantially as described.

12. In an adding machine the combination of a main operating shaft, a key lever adapted to be restored to normal position before the operation of the operating shaft, a key lever adapted to remain depressed during the operation of the operating shaft, universal control mechanism adapted to be moved in varying degree by each of said key levers, and means for preventing movement of the operating shaft when said control mechanism is moved through one degree of movement and for permitting the operation of said shaft when said control mechanism is moved through a different degree of movement, substantially as described.
13. In an adding machine the combination of a main operating shaft, a key lever adapted to be restored to normal position before the operation of the operating shaft, a key lever adapted to remain depressed during the operation of the operating shaft, universal control mechanism adapted to be moved in varying degree by each of said key levers, means for preventing movement of the operating shaft when said control mechanism is moved through one degree of movement and for permitting the operation of said shaft when said control mechanism is moved through a different degree of movement, and latch mechanism adapted to engage and latch said control mechanism when in one of its positions of adjustment, substantially as described.
14. In an adding machine the combination of a main operating shaft, a rock shaft, a universal bail bar rigidly connected with the rock shaft, an arm rigid upon the rock shaft, a pivoted stop control lever provided

near one end with a cam slot for engaging said arm, a stop segment on the operating shaft adapted to engage the pivoted stop control lever when in one position and adapted to ride thereunder when in another position, and a series of key levers adapted individually to engage the universal bail bar and depress the same to cause the stop engaging arm to move to stopping position, substantially as described.

15. In an adding machine the combination of a main operating shaft, a stop segment carried by said shaft, a rock shaft, a universal bail bar carried by the rock shaft, a pivoted stop control lever provided with a cam slot engaged by said rocking arm, the formation of the cam being such that when the rocking arm is initially rocked, the stop control lever will be moved to stopping position and thereafter upon a continued movement of the rock arm will be restored to non-stopping position, and a special key and connections for imparting to the bail bar the extreme degree of movement, substantially as described.

16. In an adding machine the combination of a main operating shaft, a stop segment carried by said shaft, a rock shaft, a universal bail bar carried by the rock shaft, a pivoted stop control lever provided with a cam slot engaged by said rocking arm, the formation of the cam being such that when the rocking arm is initially rocked, the stop control lever will be moved to stopping position and thereafter upon a continued movement of the rock arm will be restored to non-stopping position, a special key and connections for imparting to the bail bar the extreme degree of movement, and a latch bar adapted to engage and hold down the universal bail bar when moved to its extreme position, substantially as described.

HARRY LANDSIEDEL.
